UNITED STATES PATENT OFFICE.

ALBERT A. HEYMAN, OF BALTIMORE, MARYLAND, ASSIGNOR TO THE UNIVERSAL CIGAR MACHINERY CO., INC., OF BALTIMORE, MARYLAND.

METHOD OF AND APPARATUS FOR FEEDING TOBACCO TO CIGAR MACHINES.

Application filed August 9, 1922. Serial No. 580,671.

To all whom it may concern:

Be it known that I, ALBERT A. HEYMAN, a citizen of the United States, residing at Baltimore, in the State of Maryland, have invented a new and useful Method of and Apparatus for Feeding Tobacco to Cigar Machines, of which the following is a specification.

This invention relates to a new and improved method of feeding tobacco to cigar machines, or cigar bunch making machines and also to apparatus for feeding the tobacco.

Heretofore in the manufacture of cigars by machine the tobacco has been assembled and cut into bunches of uniform width, length and thickness and, in order to produce a cigar having tapered ends, it has been the practice to use V-shaped knives or like means for cutting away portions of the bunches at the ends so that, when each bunch is rolled and wrapped, the ends will be tapered. This method of producing the tapered ends of the cigars has been objectionable because it results in the formation of a waste product consisting of the cuttings. This product is ordinarily fed back to the operator feeding the machine, or to a receptacle provided therefor and it is utilized in the manufacture of inferior grades of cigars.

One of the objects of the present invention is to provide a means whereby the cutting and shaping of the ends prior to rolling the cigars is eliminated and no waste product or cuttings are produced, the entire amount of tobacco fed into the machine being retained.

A further object is to arrange the tobacco in layers prior to being cut into bunches, the layers being positioned in a novel manner relative to each other whereby less tobacco will be at the ends than at the other portions of the formed bunches, with the result that when the bunches are shaped, the resultant cigars will be tapered at their ends.

With the foregoing and other objects in view, which will appear as the description proceeds, the invention consists of certain steps in the method and certain novel details of construction and combinations of parts which will be hereinafter more fully described and pointed out in the claims, it being understood that changes may be made without departing from the spirit of the invention as claimed.

In the accompanying drawings the preferred form of the apparatus has been shown.

In said drawings

Figure 1 is a plan view of a portion of a 60 cigar making machine having a feeder combined therewith, and showing the method of arranging the layers of tobacco before being formed into bunches.

Figure 2 is a section on line 2—2, Fig. 65 ure 1.

Figure 3 is a longitudinal section through the stacked layers of tobacco shown in Figure 1.

Figure 4 is a plan view of a modified 70 form of stack.

Figure 5 is a section on line 5—5, Fig-ure 4.

Figure 6 is a section on line 6—6, Fig-ure 4.

Figure 7 is a plan view of another modified form of stack.

Figure 8 is a section on line 8—8, Fig-ure 7.

Figure 9 is a section on line 9—9, Fig-ure 7.

Figure 10 is a plan view of another form of stack.

Figure 11 is a section on line 11—11, Fig-ure 10.

Figure 12 is a section on line 12—12, Fig-ure 10.

Figure 13 is a plan view showing a layer cut to a particular shape prior to being stacked.

Figure 14 shows a layer of another shape.

Referring to the figures by characters of reference, 1 designates a feeding belt for conveying tobacco into the cigar machine, this belt being driven by any suitable means, not shown, and working under one or more wheels 2 capable of up and down movement, these wheels being mounted on the same axis 3 which, in turn, is connected by a link 4 to a lever 5 fulcrumed as at 6. The lever has an index or pointer 7 at its free end which cooperates with a graduated plate 8 to indicate the rise and fall of the wheels 2 relative to the belt. Thus the thickness of material fed under the wheels by the belt 95 can be determined readily at all times and it becomes possible for the operator to maintain the material at a substantially uniform thickness.

In the present instance the cigar machine 110

is provided with a special feeding mechanism of the same general type as that shown, for example, in my pending application No. 555,912. This mechanism includes an endless belt 9 on which the operator arranges the tobacco leaves in a single layer. This layer is carried by the belt under a roll 10 after which it is directed onto a transfer member 11. In the machine shown this member is in the form of a plate having numerous apertures 12 in which are mounted pins 13. These pins are connected to a movable head adapted to be shifted in properly timed relation with the movement of other parts of the mechanism, so as to project the pins above the plate 11. The member 11 is pivotally mounted at 14 and cooperates with a top member 15 mounted to swing about the axis of the roller 10. Apertures 16 are formed in the member 15 to receive the pins 13. The operation of the machine is such that after the layer of tobacco leaves has been directed onto the member 11 the top member 15 will descend and clamp the layer. The pins 13 will then be ejected into the apertures 16 so as to perforate the tobacco. Thereafter the member 15 is swung to the position shown in Figure 2 and the member 11 is swung to position over the belt 1 with the pins extending downwardly. During the initial portion of the movement of the member 11 the tobacco is cut or broken off upon a knife 17 that has been brought to active position by suitable mechanism. When the member arrives above the belt 1 the pins 13 are withdrawn from the layer of tobacco which will thus be deposited upon the belt. The member 11 then returns to the position shown in Figure 2 where it will receive another layer of tobacco.

The mechanism herein described does not, in itself, constitute any part of the present invention but merely provides a means whereby the method of forming the stack can be effected. For this reason it is not deemed necessary to describe the mechanism in detail. It is to be understood that it is desirable for the transfer member 11 to work about an axis obliquely disposed relative to the line of movement of the belt 1. This will result in each layer of tobacco, indicated at T, being deposited obliquely upon the belt. As the belt 1 is moved forward after each layer has been deposited, it will be apparent that the layers will be arranged in lapped relation, the rear edge of each layer resting on the belt while the front or advancing edge is mounted above the previously deposited layers. Furthermore, as the layers are obliquely disposed the longitudinal edges of the layers will be out of vertical alinement, the edges of the layers at one side of the stack of tobacco being stepped upwardly while the opposite edges of the layers overhang. Thus it will

be apparent that when the stack of tobacco is cut transversely the ends of the resultant bunches will be both obliquely disposed and beveled or substantially beveled. As there is less bulk of tobacco at the ends of the bunches when produced in this manner, it will be obvious that when a bunch is rolled a taper will be produced at the ends thereof. It becomes unnecessary, therefore, to cut the ends of the bunches in order to produce the tapered ends and, consequently, there are no cuttings produced. Instead, all of the tobacco is used in making cigars with long fillers.

While a particular means has been described and shown for depositing the layers of tobacco on the belt in the peculiar arrangement disclosed, it is to be understood that various other means may be employed for this purpose if found efficient. For example the transfer head could be moved to and fro; or the receiving belt could be moved sidewise to and fro, thus to get a stack such as shown in Figures 4, 5 and 6.

Another method would be a variable feed starting with a narrow strip and gradually widening and then repeating this operation to get a stack such as shown in Figures 7, 8 and 9. By combining a variable feed with a movable transfer head or belt a stack such as shown in Figures 10, 11 and 12 would be obtained.

Another method would be to cut with serrated or angular knives before transferring and then lay same on feed belt either at right angles or obliquely, as shown in Figures 13 and 14.

What is claimed is:—

1. The herein described step in the method of forming cigar bunches which consists in arranging in a stack, flat superposed layers of uniform area, each consisting of a plurality of leaves said layers being stepped longitudinally and transversely relative to each other.

2. The herein described step in the method of making cigars which consists in feeding into a cigar making machine a stack of superposed layers of tobacco, each layer being obliquely disposed relative to its line of travel, the corresponding edges of the layers being out of alinement.

3. The herein described step in the method of making cigars which consists in depositing on a movable support, flat layers of tobacco, said layers being of uniform area and each consisting of a plurality of leaves said layers being superposed and arranged in transversely stepped relation.

4. The herein described step in the method of making cigars which consists in depositing on a longitudinally movable support, flat layers of tobacco substantially uniform in area, each consisting of a plurality of leaves, said layers being disposed in lapped

relation to form a continuous unbroken stack.

5. The herein described step in the method of making cigars which consists in depositing on a longitudinally movable support, flat layers of tobacco substantially uniform in area, each consisting of a plurality of leaves, said layers being disposed in lapped relation to form a continuous unbroken stack 10 of less bulk at the sides than at the center.

6. The herein described step in the method of making cigars which consists in depositing on a movable support, flat layers of tobacco substantially uniform in area, each 15 consisting of a plurality of leaves, said layers being disposed in lapped relation to form a continuous unbroken stack, said layers being offset laterally relative to each other.

7. The herein described step in the method 20 of making cigars which consists in depositing on a movable support, layers of tobacco in lapped relation to form a continuous unbroken stack, said layers being offset laterally relative to each other and obliquely 25 disposed relative to the direction of movement of the support.

8. The herein described step in the method 30 of making cigars which consists in feeding to a cigar making machine a continuous unbroken stack formed of flat layers of tobacco, said layers being substantially uniform in area and comprising a plurality of leaves, the corresponding edges of the layers being out of alinement.

35 9. The herein described method of making cigars which includes arranging the tobacco leaves to form a layer, severing the layer into lengths, depositing said lengths suc-

cessively on a movably mounted support thereby to form a stack the layers of which 40 are lapped in the direction of movement of the support, the corresponding edges of the layers being out of alinement.

10. In a cigar or bunch making machine a 45 belt for receiving spread tobacco leaves to form a continuous layer, a feeding belt, means for dividing said layer into desired lengths, and means for successively transferring said lengths to the feeding belt and 50 depositing them thereon in lapped relation with their corresponding edges out of alinement.

11. In a cigar making machine a belt for 55 receiving tobacco leaves to form a continuous layer, a feeding belt, means for dividing said layer into lengths, and means for transferring the lengths successively and depositing them in superposed relation on the feeding belt obliquely to the direction of movement of said belt.

12. In a cigar making machine a belt for 60 receiving tobacco to form a layer, a feeding belt, means for dividing said layer into lengths, means for successively transferring said lengths to the feeding belt to form a 65 continuous stack of lapping layers, an indicator, and movable means supported by the stack for shifting the indicator.

In testimony that I claim the foregoing as 70 my own, I have hereto affixed my signature in the presence of two witness.

ALBERT A. HEYMAN.
